(57) **CLAIM**

The ornamental design for a neurostimulation lead, as shown and described.

DESCRIPTION

FIG. 1 illustrates a top perspective view of a neurostimulation lead, showing our new design;

FIG. 2 illustrates a top view thereof;

FIG. 3 illustrates a front end view thereof;

FIG. 4 illustrates a left side view thereof, the right side view being identical;

FIG. 5 illustrates a bottom view thereof;

FIG. 6 illustrates a rear end view thereof; and,

FIG. 7 illustrates a cross sectional view taken along line 7—7 thereof.

The broken line showing in FIGS. 1, 2 and 4-6 is for illustrative purposes only and forms no part of the claimed design. Although references to the drawings have been made with respect to perspective, top, bottom, left side, right side, front end and rear end, it shall be appreciated that the forgoing orientations are used for reference purposes only and the model of the present invention may be disposed in any orientation.
